Patented Feb. 20, 1968

210,203

EQUIPMENT OPERATOR'S CABIN

Ernest Hofmann-Igl, Mitterfeld, Germany, assignor to
Firma Georg Fritzmeier KG., Grosshelfendorf, über
Munich, Germany

Continuation-in-part of design application Ser. No. 4,271,
Oct. 13, 1966. This application Feb. 13, 1967, Ser. No.
5,798

Claims priority, application Germany Apr. 15, 1966

Term of patent 14 years

(Cl. D14—3)

Fig. 1

Fig. 2

Fig. 3

Fig. 4

FIGURE 1 is a perspective view of an equipment operator's cabin embodying the new design of the present invention and showing the back and one side of the cabin;

FIGURE 2 is another perspective view of the cabin of FIGURE 1 showing the front and the other side of the cabin;

FIGURE 3 is a side view of the cabin of FIGURE 1;

FIGURE 4 is a top plan view of the cabin of FIGURE 1.

The tractor shown in broken lines is included for illustrative purposes only.

This is a continuation-in-part of design application Ser. No. 4,271, filed Oct. 13, 1966, and now abandoned.

What I claim is:

The ornamental design for an equipment operator's cabin, substantially as shown and described.
